No. 814,904.

PATENTED MAR. 13, 1906.

C. E. EMORY.

COMBINED WASHBENCH AND STEP LADDER.

APPLICATION FILED MAY 19, 1903.

UNITED STATES PATENT OFFICE.

CHARLES E. EMORY, OF PITTSBURG, PENNSYLVANIA.

COMBINED WASHBENCH AND STEP-LADDER.

No. 814,904.

Specification of Letters Patent.

Patented March 13, 1906.

Application filed May 19, 1903. Serial No. 157,759.

To all whom it may concern:

Be it known that I, CHARLES E. EMORY, a citizen of the United States of America, residing at Pittsburg, in the county of Allegheny and State of Pennsylvania, have invented 5 certain new and useful Improvements in a Combined Washbench and Step-Ladder, of which the following is a specification.

This invention relates to certain new and 10 useful improvements in combination step-ladder and bench.

My invention consists in the novel details 15 of construction, a preferable embodiment of which is described in the specification and illustrated in the drawings, wherein—

Figure 1 is a perspective view of my combined step-ladder and bench when used as a step-ladder. Fig. 2 is a side view of my combination step-ladder and bench when used as 20 a bench.

Referring to the drawings, 1 represents 25 side rails, and mortised therein are strips 2, which serve as steps for step-ladder. The bench-legs 4 and 4' are pivoted to the side rails, as at 5, and abut against the inclined face of the bracing-plates 6. This prevents spreading of the legs when set up as illustrated in Fig. 2. The bracing-plates comprise 30 bases secured to the sides of the ladder, angular portions 6^a, and extremities 6^b, back of which the legs lie in engagement with the angular portions of the plates. Legs 4' 4' are provided with hooks 7, which when ladder is 35 in use enter eyes 8 on under side of bench-seat 9, thereby preventing the same from collapsing.

The bench-seat or ladder-support 9 is hinged, as at 10, to a rigid strip 11, secured to upper rest 12. The free end of the seat 40 or support 9 has a projection 9', extending

centrally and nearly across the entire width thereof. The bottom of the ladder is also provided with a rigid strip 11', having a recess 12', adapted to receive the projections 9' of the seat when the device is folded or being used as a bench. This arrangement provides a securing means for the seat and prevents any undue transverse movement thereof. In the ladder formation legs 4 4 are held along the side strips by the use of hooks 13, 45 entering eyes 14.

When the device is not in use or ready for shipment, the legs will be in the position as shown in dotted lines of Fig. 2, legs 4 4 being held by hooks 13 and 4' 4' by hooks 15, engaging eyes 16.

From the foregoing it will be evident that I have provided a simple, strong, and durable device for the purpose set forth, and

What I wish to claim is—

In a step-ladder, legs pivoted to the side of the ladder, the legs at one end also serving as braces, bracing-plates for the legs secured to the sides of the ladder, a rigid strip extending across the ladder at the top and bottom thereof, the bottom strip having a recess in one edge thereof, a combined seat and support hinged to the upper strip at one end, a projection on the opposite end adapted to fit in the recess of the lower strip, means for securing the legs to the ladder and means for securing one pair of legs to the support.

In testimony whereof I affix my signature, in the presence of two witnesses, this 16th day of May, 1903.

CHARLES E. EMORY.

Witnesses:

JOHN NOLAND,
W. J. FULTON.
